US00D539775S

(12) **United States Design Patent** (10) **Patent No.:** **US D539,775 S**
(45) **Date of Patent:** **** Apr. 3, 2007**

(54) **WIRELESS COMMUNICATION DEVICE**

(75) Inventors: **Cheol Woo Park**, Chicago, IL (US);
Sung-Gul Hwang, Evanston, IL (US);
Paul M. Pierce, Grayslake, IL (US)

(73) Assignee: **Motorola, Inc.**, Schaumburg, IL (US)

(**) Term: **14 Years**

(21) Appl. No.: **29/231,451**

(22) Filed: **Jun. 3, 2005**

(51) **LOC (8) Cl.** **14-03**

(52) **U.S. Cl.** **D14/138**

(57) **CLAIM**

The ornamental design for a wireless communication device, as shown and described.

DESCRIPTION

FIG. 1 is a front perspective view of an ornamental design of a wireless communication device showing our new design.

FIG. 2 is a rear perspective view thereof.

FIG. 3 is a front orthographic view thereof.

FIG. 4 is a rear orthographic view thereof.

FIG. 5 is a left side orthographic view thereof.

FIG. 6 is a right side orthographic view thereof.

FIG. 7 is a top orthographic view thereof.

FIG. 8 is a bottom orthographic view thereof.

FIG. 9 is a perspective view of an ornamental design of a second embodiment of a wireless communication device showing our new design.

FIG. 10 is a rear perspective view thereof.

FIG. 11 is a front orthographic view thereof.

FIG. 12 is a rear orthographic view thereof.

FIG. 13 is a left side orthographic view thereof.

FIG. 14 is a right side orthographic view thereof.

FIG. 15 is a top orthographic view thereof; and,

FIG. 16 is a bottom orthographic view thereof.

The broken lines immediately adjacent the shaded areas represent the bounds of the claimed design while all other broken lines are directed to environment and are for illustrative purposes only; the broken lines form no part of the claimed design.
